W. Steel Johnson,

ATTORNEY

UNITED STATES PATENT OFFICE.

JAMES HERMAN ABBOTT, OF PHILADELPHIA, PENNSYLVANIA.

PROCESS OF PRODUCING DENTAL SUCTION.

1,092,553.

Specification of Letters Patent.

Patented Apr. 7, 1914.

Original application filed August 9, 1911, Serial No. 643,111. Divided and this application filed May 18, 1912. Serial No. 698,103.

To all whom it may concern:

Be it known that I, JAMES HERMAN ABBOTT, a citizen of the United States, residing at 2534 South Twentieth street, Philadelphia, in the county of Philadelphia and State of Pennsylvania, have invented a certain new and useful Process of Producing Dental Suction, of which the following is a specification.

10 The purpose of my invention is to secure a preferably flat apertured dental suction disk to a plate and cup it by pressure about an annular portion of the disk and greatest at a short distance from the edge of its central aperture. I prefer to apply the pressure by means of a hollow tubular rivet and a washer having an annular rib which engages the material of the disk. I avoid vulcanization, make my process applicable to 20 old or new plates and permit initial manufacture of a suitable seat for later application of the suction without interfering with the use of the plate as plates have previously been used until such a time as a separate suction is desired and applied.

Among various means by which my invention may be and is carried out, I have selected the form illustrated because of its simplicity, effectiveness and inexpensiveness 30 and ease and speed of application.

Figure 1 is a broken vertical section through the preferred form of construction for carrying out my invention, showing the parts in separated position. Fig. 2 is an enlarged broken section corresponding to Fig. 1 with the parts in assembled position. Fig. 3 is a section at right angles to Figs. 1 and 2 showing a dental plate prepared for application of my invention.

40 This application is a division of my application No. 643,111, filed August 9, 1911. Further detail in regard to variations in the means by which my process may be carried out will be found in this application.

45 The dental plate 1, corresponds in general contour to the shape of the roof of the mouth in which it is intended to be applied and is normally provided with a vacuum recess 2, whose floor is usually quite curved 50 in the section corresponding to Fig. 3, but nearly straight in all sections corresponding to Figs. 1 and 2. In order to prepare the plate for application of my dental suctions, I form an additional recess or sub-recess, here illustrated at 3, by any suitable means,

during or subsequent to the production of the plate as may be desired. I have shown this recess in its simplest form, as having a flat floor, but other contours will effectively carry out my invention provided the floor be not convexed to any considerable extent. The best practice of my process requires that the floor of the recess 3 shall be substantially a surface of revolution, *i. e.* having points at equal distance from the axis of the aperture 4 at the same height axially throughout that annular portion of the floor of the recess against which the pressure will be brought to cup the disk.

55 In the application of rubber disks as so far produced, there has been a tendency either to wedge the disks outwardly from the aperture by the character of fastening used or to distribute the pressure upon the disk with substantial uniformity over a relatively wide portion of the disk and of the floor upon which it rests. I have discovered that the best results in retention and sealing of the suction disk and in uniformity, effectiveness and permanence of cupping 60 require that the greatest pressure upon the disk be exerted at a short distance outwardly from the aperture of the disk and extend over but a relatively narrow annular space and that approximately the same pressure be applied upon the disk in all directions from the center of the disk. This requires a certain relation between the washer and the bottom surface or floor of the recess 3, rather than a condition of the bottom 65 alone, provided the floor be not unduly convex to reduce unduly the cupping effect obtained. I have also discovered that existing plates of all materials may be prepared easily and quickly for disk application in accordance with the principles stated above by suitable boring and counterboring by 70 means already in the dentist's possession and that the disk may then be set quickly and surely by means of a rivet set and coöperating rivet parts suited to the surface of the counterbore.

75 I prefer to use an initially flat rubber disk 5 of existing form and to get all of my cupping action by means of the clamp which 80 holds the disk.

85 In the application of my disk, it is not necessary to utilize the edges 6 of the counterbore at all, though they may form a partial support against the cup in case of 90

95 ultimate failure of the clamp. 100

mate breaking down of the same. These edges, therefore, need not be uniform in height about the sub-recess.

In order to reduce the plate as little as possible, the counterboring to form the sub-recess 3 will ordinarily stop as soon as the entire surface to be used has been cut to the contour desired.

The device which I utilize for compressing the disk to cup it comprises a rivet 7 and washer 8. I use a solid head rivet to close the space through the plate and make it tubular, as at 9, because of the additional vacuum space thus provided, the ease of turning the tubular end, and the ease of removing the turned end for replacement of my cup when required. Since the head of the rivet is placed upon the labial side of the plate, I there recess the plate, as at 10, utilizing any suitable sealing means between the head and the plate, as desired. The washer 8, apertured at 11, is formed upon the side next to the plate as an annular rib 12, giving its closest approach axially to the bottom or floor of the recess 3, at a short distance radially from the aperture. The opposite face of the washer is also shown as annularly recessed, corresponding to the annular rib, to provide space within which the end 13 of the tubular rivet may be turned and to give additional vacuum space, resulting in a washer of substantially uniform thickness throughout.

In order to bring pressure to bear upon the disk to a greater extent at a short distance from the aperture than adjoining the aperture and thus to cup the disk without tendency to wedge it outwardly from the aperture, I compress the disk between the washer and the bottom surface of the aperture 3, and retain the parts in this position by turning the tubular end of the rivet 8.

I have shown the jaws 14, 15, anvil 16 and head 17 of a pair of rivet-setting pliers by which the washer may be seated and the rivet set, though obviously other means could be utilized. The anvil is flat at 18, corresponding to the preferred shape of the head of the rivet, and the head 17 is provided with a central projection 19 to guide it into the rivet and hold the latter in fixed centered position. The head 17 also in the construction illustrated, carries an annular rib or projection 20 for the purpose of engaging the washer to press it into place

while the intermediate portion 21 of the head is turning the rivet about the inner edge of the washer.

I prefer to slope the outer part of the face of the washer rather more abruptly away from the seat than the inner part so as to permit the disk to cup as abruptly as it will under the clamping action and at the same time making the rib of the washer as blunt as possible in cross sectional contour to avoid cutting or excessive crushing of the disk, usually rubber, under it.

Though I bring the greatest pressure upon the disk at a short distance outside of the inner edge of the disk there is some advantage in continuing the washer inwardly from this point at an angle diverging from the seat to continue its contact with the disk, preferably, all the way to the inner edge of the disk.

What I have designated as a rib is preferably circular and uniformly spaced from the aperture for the rivet, though other continuous forms coöperating with the seat would evidently cup the disk.

In my use of the term "disk" in the claims, I have considered it as including forms, whether flat or partially cupped, which were advantageously clamped or used in the manner called for by the claims to give or increase the cupping.

Having thus described my invention, what I claim as new and desire to secure by Letters Patent is:—

1. The process of cupping disks for dental suctions, which consists in compressing an apertured disk against a seat by applying cupping pressure annularly about the aperture greater at a short distance from the edge of the aperture than at its edge and uniformly about the length of the annulus.

2. The process of placing a dental suction, which consists in boring a hole entirely through the plate, counterboring the hole thus formed to provide an annularly even surface about the hole, and compressing an apertured rubber disk upon the surface so formed by annular means having greatest compression at a distance from the edges of the hole and aperture.

JAMES HERMAN ABBOTT.
